SYMMETRICAL FLUE BOILER WITH CENTRAL FIREBOX AND OFFSET MAGAZINE

William Herbert Smith, East Molesey, England

Application October 29, 1948, Serial No. 57,250
In Great Britain November 3, 1947

6 Claims. (Cl. 122—130)

1

This invention relates to boiler furnaces, more particularly for central heating by hot water or steam, of the kind provided with a fuel compartment which feeds fuel to a combustion zone at the bottom of the furnace through which primary air is forced, the hot gases from this combustion zone passing through internal flues in the boiler.

From one aspect the invention provides a boiler furnace of the kind referred to in which internal flues pass from the combustion zone to the top of the boiler and then downwardly towards the bottom, the section of the downwardly extending parts of the flue becoming more elongated below a fuel hopper at the rear of the boiler so as to allow of correct area being provided throughout for the flue gases while allowing the fuel hopper to be the full width of the boiler and the firebox to be of maximum width. For example the downwardly extending flues may be of rectangular section with their longer dimension running from front to back of the boiler and this longer dimension increases below the level of the fuel compartment and the smaller dimension decreases gradually from top to bottom.

The primary air is delivered through a tuyère situated within the fuel in the firebox and directed downwardly.

From another aspect, the invention provides a boiler of the kind referred to in which primary air is delivered by a blower under the control of a thermostat operating in accordance with the temperature of the water. The thermostat may act to switch off an electric motor driving the blower when the water temperature rises above a pre-determined value and to switch it on when the water temperature has fallen to another pre-determined value.

Other parts of the invention are embodied in the preferred form of boiler which will now be described in some detail by way of example with reference to the accompanying drawings in which:

Fig. 1 is a front elevation partly in section of a preferred form of boiler,

Fig. 2 is a section on the line II—II of Fig. 1, and

Fig. 3 is a plan view, partly in section on the line III—III of Fig. 1.

In this form, the boiler 1 is substantially rectangular in plan and the fuel hopper 2 extends across the full width at the back. The fire box 3 is immediately below the fuel hopper.

A heat chamber 4 extends vertically from the fire box 3 and from this chamber flues 5 pass downwardly at each side to the bottom 6 of the

2

boiler (beneath the fire box) and thence upwardly at the rear to a flue pipe 7.

The heat chamber 4, firebox 3 and the side flues 5 are all surrounded by the water being heated, the partitions 8 between the heat chamber and the side flues, the imperforate bases 9 and rear wall 10 of the fire box and the walls 11, 12 and top 13 of the boiler and the wall 110 between the boiler and the hopper all being hollow and 10 in communication with one another. The heat chamber 4 is divided by a central partition 14 depending from the top of the boiler, and this partition is also hollow and in communication with the rest of the water spaces. The partition 15 14 thus forms an economiser. It will be seen that the water in the boiler is in effect distributed through a large number of relatively narrow passages so that there is a very large surface in contact with the heating gases which promotes efficiency in heating.

The side walls 8 of the heat chamber 4 slope inwardly from the bottom to the top and as these walls are of uniform thickness, this gives (with vertical side walls to the boiler) a gradually decreasing width to the side flues 5. To preserve the proper cross-sectional area for the flue gases, the dimension of the flues 5 from back to front of the boiler increases from about the level of the bottom of the fuel hopper 2 to the boiler bottom 6 as shown in dotted lines in Figs. 2 and 3. This arrangement enables the fuel hopper to be of the full width of the boiler while the fire box at the bottom of the boiler is of maximum width.

The fire box 3 is supplied with fuel from the hopper 2 through a throat 15 designed to give correct formation to the fuel. The throat is flared and deflectors 16 are also provided to guide the fuel into the fire box so as to give a correct formation to the fuel therein. The orifice leading from the coal hopper is at such a height and is so shaped that it causes the coal falling by gravity to fall sufficiently forward adequately to cover the nose of the tuyère, but is restricted sideways by the deflectors 16 so as not to form too heavy a coal bed adjacent to the sides of the boiler.

The supply of fuel is controlled by a shutter 17 at the bottom of the hopper, operable by means of a handle 18 at the side. A fire door 19 at the front of the apparatus provides access to the fire box 3 and a sight glass 20 is provided in this door.

Air is supplied to the fire through a water-jacketed tuyère 21 arranged below the normal fuel level (indicated at 22) and directed downwardly so that the air passes first downwardly 55 and then upwardly through the fuel to the heat

chamber. The water-jacketed tuyère 21 acts as a "hot-spot" in the fire.

The tuyère 21 projects into the fire box from the back wall 10 and is normally completely covered by the fuel.

The water in the jacket 23 of the tuyère connects with the water in the rest of the boiler and the top of the jacket is sloped to assist the natural convection of the water and to guide the fuel into correct position.

Air is forced through the tuyère 21 by a blower 24 situated at the rear of the fire box and driven by an electric motor or other prime mover 25. A circulating pump (not shown) by which the water in the system is circulated, may be mounted on the same shaft as the blower.

Secondary air to ensure complete combustion is led from the blower 24 through hoses 30 to secondary air inlets 31 which open into the heat chamber 3 above the normal level of the fuel.

The water inlet to the boiler may be through the circulating pump. Two water outlets 27 where this is used but as shown is at 26, one at each side are provided at the top of the boiler for alternative connections or for use with domestic supply and central heating respectively.

A thermostat 28 operated by the temperature of the outlet water controls the motor driving the blower 24 by means of a conventional control circuit 28' which is diagrammatically shown in Fig. 3. It is arranged to switch the motor 25 off and stop the blower when the temperature reaches a predetermined value and to switch the motor on, starting the blower, when the temperature has fallen below a lower predetermined value.

During idling periods (when the motor is not running) air for combustion is supplied to the tuyère under the influence of the normal chimney draught through an idling valve 32 in the blower casing. This valve is closed automatically when the blower is in operation by the pressure of the air and opens under gravity when the blower stops.

Cleaning throats 33 for the side flues are provided in the top of the boiler and a base cleaning throat 34 is provided to the flue below the fire box.

The boiler is enclosed in a casing 35 with asbestos or other insulation 36 between the casing and the boiler shell. There is a cover 37 to this casing which may be raised to allow access to the cleaning throat 33 and the safety valve 38. The lid 39 of the fuel hopper is in this cover.

It will be understood that the invention is not restricted to the details of the specific form described which can be varied without departure from the broad ideas underlying them.

I claim:

1. A boiler comprising a fire-box in the bottom thereof, a flue having a length substantially co-extensive longitudinally with that of the upper part of the boiler and extending upwardly from the fire-box to the top of the boiler and then laterally and downwardly to the bottom thereof, and a fuel hopper at the back of the boiler behind said flue and above said fire-box permitting the fuel hopper to extend the full width of the boiler, said hopper having a fuel discharge port opening into the top of said fire-box, and the downwardly extending portion of said flue being longer from front to back below said fuel hopper than above said fire-box to provide sufficient transverse flue area and to permit the fire-box to be of maximum width.

2. A boiler according to claim 1 in which the

flue is divided by a central vertically disposed hollow partition forming two flues symmetrically arranged in opposite sides of the boiler, the hollow interior of said partition being in communication with the boiler so that the partition forms an economizer.

3. A boiler according to claim 2 in which the outer walls of the boiler are substantially vertical, and hollow partitions dividing the upwardly and 10 downwardly extending portions of said flues and being inclined inwardly from the bottom to the top so that the outermost flue portions are of decreasing width from top to bottom enable maximum width of said fire-box, the lower rear edges 15 of said partitions being declined rearwardly toward the bottom so that the outermost flue portions adjacent the fire-box are of increasing length and of substantially uniform cross-sectional area throughout, the hollow interiors of said partitions being in communication with the remainder of the water space in the boiler.

4. A boiler, as defined in claim 1, in which the flue and the bottom of the fire box are defined by hollow walls in communication with said boiler for containing the water to be heated, and a downwardly directed water jacketed tuyère within the fuel zone in the fire box, the water jacket of said tuyère being in communication with the remainder of the water space in the boiler.

5. A boiler, as defined in claim 1, comprising a water jacketed tuyère in said fire box and in communication with said boiler, said hopper discharge port being located above the tuyère so that fuel falling by gravity is led sufficiently forward to cover the nose of the tuyère, and deflectors extending downwardly from said hopper beside said port to restrict the flow of fuel sideways and prevent the formation of a heavy fuel bed adjacent the sides of the boiler.

6. A boiler, according to claim 1, comprising a water jacketed tuyère in said fire-box and in communication with said boiler, a blower and a connection between said blower and said fire box beneath said tuyère by which primary air is delivered under said tuyère by said blower, a thermostat subject to the temperature of the water in said hollow walls and controlling said blower, a by-pass from said blower into said fire box beyond said tuyère in which secondary air is fed to the fire box above the fuel bed from the blower, and an automatically operating idling valve in the connection of the blower to the fire box and through which air for combustion is supplied when the blower is not in operation.
